UNITED STATES PATENT OFFICE.

GEORGE L. FOOTE, OF NEW YORK, N. Y., ASSIGNOR TO FOOTE, PIERSON & COMPANY, OF NEW YORK, N. Y., A FIRM.

LIGHTNING-ARRESTER.

No. 857,045.

Specification of Letters Patent.

Patented June 18, 1907.

Application filed December 29, 1906. Serial No. 349,937.

To all whom it may concern:

Be it known that I, GEORGE L. FOOTE, a citizen of the United States, and a resident of New York city, borough of Brooklyn, county of Kings, State of New York, have made certain new and useful Improvements in Lightning-Arresters, of which the following is a specification.

This invention relates to apparatus adapted to protect electrical instruments and machinery from discharges of atmospheric electricity and from currents of electricity of abnormally high electro-motive force.

The object of the invention is to supply a portable, compact, simple and effective device specially useful in cases where a large number of wires or conductors are grouped in a small space as at a cable terminal or in a box elevated on a pole.

The improved lightning arrester consists of a cylindrical foundation of insulating material on which is a convoluted conductor, the convolutions increasing in diameter from each end of the cylinder to a point midway the poles of the major axis. This is inclosed in a corrugated sheet metal casing designed for connection with the ground; by this means the sparking distance is graduated; it is desirable to place the shortest sparking distance toward the outside line or conductor so that as a storm approaches the first or outside convolutions of the arrester will first discharge and as the storm comes nearer, its potential rising, successive convolutions will take part in the discharge, thus increasing the capacity; it is to insure the placing of the shorter sparking distance to the line side that I provide the double truncated cone form or core; this arrangement insures the location of the shortest sparking distance to line as the linemen cannot connect it into circuit improperly, and this arrangement also provides for way stations where storms are liable to approach from either direction; this sheet metal is made sectional to avoid entirely inclosing the coil as it is found that when the edges of the sheet metal casing are brought together the choke coil functions of the helical conductors are impaired. Outside the sheet metal cylinder is a cylinder of insulating material which is preferably fireproof material. The cylindrical foundation is hollow and within the cylinder is a fuse or section of fusi-

ble conductor with suitable terminals for the electrical connections. The arrester is provided with screw socket terminals and a base block of insulating material; these base blocks are of a regular geometrical form and are provided with projections and depressions in or on their meeting edges, the projection in one base registering with a depression in the adjacent base.

The accompanying drawings illustrate the invention:

Figure 1 is an elevation of the complete arrester partly in section showing two arresters on a single base; Fig. 2 is a plan view of the same partly in section; Fig. 3 is a section through the base block on the line 3, 3, Fig. 4; Fig. 4 is a plan view of base blocks showing their registering contact surfaces and the electrical connections.

In Fig. 1, *a* is a cylindrical foundation of insulating material, preferably porcelain, the upper end terminates in a ring *20*; it has a hollow tapered interior *21*; its outer surface has two sets of helical grooves *10*, the diameter of each convolution increasing from the ends of the cylinder toward the center or point midway the poles where there is a ring or partition *d* formed with the foundation *a*; *w* is a bare conductor wound in the helical groove *10*. There is a slot *11* through the partition *d* through which conductor *w* passes. The binding-post *22* forms a terminal for one end of the conductor *w*, the other end of conductor *w* is electrically connected to a screw socket terminal *s*; terminal *s* is a spun sheet metal terminal having alternate grooves and depressions helically arranged; the terminal *s* fits a fixed terminal *t* of similar outline and material; terminal *t* is fixed in a base block of insulating material *b*, by this means the arrester may be readily inserted and removed. The terminal *t* is connected by a metal strip *23* with a binding-post *24* fixed in the base block *b*, (see Fig. 4); *25* is a binding-post on the base block connected to a metal strip *26* having a screw terminal *27* at the center of the open bottom socket terminal *t*. The end of the strip *27* has a screw-threaded hole.

f is a section of fusible metal inclosed in a suitable case, on the case is a screw terminal *28* which engages with the screw-threaded hole in the strip *27*; the upper end of the fuse *f* has a binding-post terminal *29* which

is connected with the binding-post 22 by means of a strap 30; this strap 30 is suitably slotted to properly engage with the screw terminals 22 and 29. The base block *b* referred to is of insulating material, as wood or porcelain, and is preferably arranged to receive two arresters, although one or three or more may be placed on a single block. Each block is provided with a metal strap 9 connected with a binding-post terminal 31 to which the ground wire is connected. At or near the center is a hole *h*, shown in dotted lines in Fig. 2, through which a screw is passed to fix the block in position. The edges of the block are provided with depressions 40 and projections 41 so arranged that the projection on one block will register with the depression on the adjacent block. This arrangement of registering projections with a single screw hole for each block forms a simple and secure means of holding these blocks in position, as against a vertical wall, for instance. There is a corrugated sectional cylinder or casing of sheet metal *c* arranged outside coiled conductor *w*; this cylinder is incomplete, a section is omitted between lines parallel with the axis and separated 10 or 12 degrees. This is done to avoid interference with the choke coil action of the coiled conductor *w* which would result if the cylinder were complete with its edges electrically united. I call this a sectional cylinder. It is of uniform diameter and is centered by the partition *d* at the center of the foundation *a*. It also rests upon the seat 42 at one end of the foundation *a* and upon the seat 43 at the other end. The cylinder *c* is corrugated with acute angular corrugations, the object being to surround the conductor *w* with acute angular points or lines as it is found that this facilitates the discharge of high potential electricity. The cylinder *c* has a flaring metal ring *r* at the bottom and the ring *r* laps onto the ground contact strip *g*; the ring *r* is preferably soldered to the cylinder *c*. Outside the corrugated cylinder *c* is placed a jacket *j* of insulating material and preferably of fireproof insulating material like asbestos, the object of this is to guard against fire risk. The location of the fusible section *f* on the interior of the fireproof foundation *a* is also an efficient protection against the same risk.

By arranging the ground contact in a straight line, that is, the wall of the corrugated cylinder *c* and by graduating the distance of the helical conductor *w* with respect to this line the discharge of electricity of varying potential is provided for and by the double taper arrangement of the conductor the fusible section *f* is always on the outside of one section of the coil in the electrical connection with the main line.

What I claim and desire to secure by Letters Patent is:

1. In a lightning arrester the combination of a tapered core of insulating material having a helical groove in its surface, a bare conductor supported in said groove and an insulated conducting medium fixed parallel with the axis of said core and in close proximity to said conductor. 70

2. In a lightning arrester the combination of a core of insulating material tapered from the center toward each end and having a helical groove in its surface, a bare conductor supported in said groove and an insulated conducting medium fixed parallel with the axis of said core and in close proximity to said conductor. 75

3. In a lightning arrester the combination of a tapered core of insulating material having a helical groove in its surface, a bare conductor supported in said groove and an insulated sheet of conducting material arranged 85 to form an incomplete cylinder, fixed parallel with the axis of said core outside of and in close proximity to said conductor.

4. In a lightning arrester the combination of a core of insulating material having a tapered axial passage from end to end, a helical conductor supported upon the surface of said core, an exterior conductor in close proximity insulated therefrom and an inclosed section of fusible conductor located in the tapered interior of the core and connected in series with the helical conductor. 95

5. In a lightning arrester the combination of a core of insulating material having an axial passage extending from end to end, a helical conductor supported upon the surface of said core, an exterior conductor in close proximity to but insulated from said helical conductor, a section of fusible conductor inclosed in a protecting tube of insulating material located in said axial passage in the core, a screw terminal for said fusible section engaging a screw socket in the bottom of said passage, a screw terminal for the upper end of said fusible section and a link of conducting material for uniting the terminals of the helical coil to the fusible section. 105

6. In a lightning arrester the combination of a suitable core of insulating material, a helical conductor suitably supported thereon and an external ground contact fixed in close proximity parallel with the major axis consisting of a curved sheet of metal having crimps or corrugations in its surface parallel with the axis of the core. 115

7. In a lightning arrester the combination of a suitable core of insulating material, a helical conductor supported thereon, an external ground contact fixed in close proximity parallel with the major axis, consisting of a curved sheet of metal having crimps or corrugations in its surface arranged parallel with the axis of the core and a cylinder of insulating material inclosing said curved sheet of metal. 125

8. The combination of a series of insulating base blocks, a lightning arrester for each block consisting of a line contact and a ground contact in close proximity, a cylinder one edge and a depression on the other edge 10 of each base block arranged to engage or register with similar projections and depressions on adjacent base blocks.

5 inclosing said contacts, means for separably connecting each cylindrical arrester to its base block and means for uniting each base block with an adjacent block to secure accurate alinement consisting of a projection on
